SINGLE TRIGGER MECHANISM FOR DOUBLE
BARRELED FIREARMS

Harry E. Howland and Nestor F. Smith, Ithaca,
N. Y., assignors to Ithaca Gun Company,
Ithaca, N. Y.

Application July 13, 1932, Serial No. 622,336

8 Claims. (Cl. 42—42)

This invention relates to certain new and useful improvements in single trigger mechanism for double barreled firearms.

The primary object of the invention is to provide a single trigger mechanism for double barreled firearms, the trigger mechanism being non-selective and firing from right to left, it being understood however, that the firing mechanism associated with each barrel may be so designed to permit the firing to be from left to right.

A further object of the invention is to provide a firearm of the double barreled type embodying single trigger mechanism for each barrel with a slide member controlled in its action by the first firing mechanism to form an interlocking connection between the single trigger and the second firing mechanism with the slide guided in its movement through a slot in the lower tang or bottom wall of the gun frame and also guided in its move through a passageway or slot in a block member rising from the lower tangs.

A further object of the invention is to provide a firearm of the foregoing character wherein the slide member that forms an interlocking connection between the single trigger and the sear of the second firing mechanism is in constant operative relation with respect to the trigger with means to permit pivotal movement of the slide when the trigger is initially operated for the firing of the first firing mechanism, the connection between the slide and trigger being of a type to permit sliding movements of the slide independently of the trigger.

It is a further object of the invention to provide a firearm of the foregoing character wherein the sear of the second firing mechanism has a block member rising therefrom to be engaged by a tensioned inertia piece pivotally suspended from the upper tang of the frame to prevent unintentional firing operation of the second firing mechanism in the presence of recoil during operation of the first firing mechanism.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary side elevational view of the gun frame and portions of the barrels with the firing mechanisms in cocked positions, looking at the right side of the gun;

Figure 2 is a fragmentary side elevational view of the left side of the gun with the first or right

hand firing mechanism operated, the slide being pivotally raised rearwardly of the sear of the second or left hand firing mechanism with the inertia piece moved rearwardly to overlie the sear of the second firing mechanism to prevent unintentional firing thereof;

Figure 3 is a fragmentary side elevational view, similar to Figure 2, showing the trigger released after operation of the first firing mechanism, the slide lowered and moved forwardly to engage beneath the sear of the second or left hand firing mechanism for the operation thereof;

Figure 4 is a cross-sectional view taken on line 4—4 of Figure 3, showing the slide forming interlocking connection between the single trigger and the sear of the second firing mechanism movable in a slot formed in the bottom wall or lower tang of the gun frame and in a block rising from the bottom wall or tang; and

Figure 5 shows perspective views of the firing mechanisms.

Referring more in detail to the accompanying drawings, there is illustrated a single trigger mechanism for double barreled firearms wherein the firearm includes a gun frame 10 provided with right and left barrels 11 and 12 respectively, the firearm being of the break-down type embodying a top lever 13 with upper and lower tangs 14 and 15 respectively projecting rearwardly of the frame 10. The extreme rear ends of the upper and lower tangs 14 and 15 are connected by a bolt 16 while the tangs are further connected together and braced intermediate their ends by the bolt 17 depending from the upper tang 14 and engaged at its lower end with the block 18 rising from the lower tang 15. The reference numeral 19 designates a part of the bolting mechanism of the gun and extends rearwardly of the frame portion 10 to occupy a position between the upper and lower tangs 14 and 15.

The trigger 20 carries a plate 21 extending through a slot 22 provided in the lower tang 15 and also through the slot 22a in the block 18 as shown in Figure 4, the trigger plate 21 having an opening 23 in one end thereof as shown in Figure 5 for pivotal mounting on the pin 24 carried by the block 18. The firing mechanism for the right hand barrel 11 includes a hammer 25 having a notch 26 adjacent its pivotal end 27 to be engaged by the end 28 of the sear 29 that is pivotally mounted as at 30. A cross pin is carried by the upper edge of the trigger plate 21 and projects at opposite sides thereof as at 31 and 32, see Figure 5, the pin end 30 being

positioned beneath the free end of the sear 28 and normally maintained in engagement with the sear 28 by the usual sear spring and also the wire spring 32 engaged with the pin end 30 as shown in Figure 1.

The firing mechanism for the left hand barrel 12 as shown in Figs. 2, 3 and 5 includes the hammer 33 having a notch 34 engaged by the end 35 of the sear 36 that is pivotally mounted 10 as at 37, the rear end of the sear 36 carrying a lateral arm 38 directed toward the sear 28 and positioned rearwardly of the block 18. For purposes presently to appear, the rear end of the sear 36 carries a block 39 rising therefrom.

15 The cross pin carried by the trigger plate for the operation of the sear 28 of the right hand firing mechanism moves in a zone spaced from the operative end of the sear 36 of the left hand firing mechanism and to form communication 20 between the cross pin on the trigger and the sear of the left hand firing mechanism, there is provided a slide member illustrated in the several figures and in detail in Figure 5 as including a plate 40 having a straight lower edge 41 moving 25 in the slot 42 parallel with the slot 22a in the block 18 and also in the slot 42a in the lower tang 15. The slide plate 40 is permitted both sliding and pivotal movement by means of the slot 43 in the plate 40 receiving the trigger pivot 30 pin 24. In view of the location of the bolting mechanism 19 rearwardly of the frame 10 and between the upper and lower tangs 14 and 15, the forward end of the slide plate 40 has been 35 designed to escape the bolting mechanism in its sliding movement and for operative engagement with the hammer 25 of the right hand firing mechanism, the forward end of the slide plate 40 carrying angle arm extensions 44 and 45 with the free end of the arm 45 engaged with 40 the hammer 25 so that when the hammer 25 is in cocked position, the slide plate 40 is moved rearwardly, guided in such movement by the pivot pin 24 of the trigger and also by the slots 42 and 42a in the block 18 and tang 15, the 45 slide plate 40 moving rearwardly against tension of the spring 46 shown in Figure 2.

The connection between the trigger pin 31 and slide plate 40 includes an upper opening slot 47 in the rear end of the trigger plate 40 into 50 which the trigger pin 31 extends and is confined therein by the forwardly extending lug 48 shown in Figures 2, 3 and 5 as overhanging the slot 47.

The firing mechanisms are provided with a safety device for rendering them inoperative, the 55 safety device being manually operable while the usual rod associated with the bolting mechanism for the automatic setting of the safety device had to be done away with to provide a clearance for the mounting of the coil member or inertia 60 piece. The inertia piece 49 of triangular formation is pivotally suspended as at 50 from the upper tang 14, being tensioned as at 51 and mounted with relation to the block 39 carried by the sear 36 of the left hand firing mechanism 65 to be moved to a position overlying the block 39 during recoil action to prevent accidental firing of the second firing mechanism, the inertia piece 49 carrying a stop lug 52 for limiting recoil movement of the inertia piece and 70 assuring a recoil position thereof during action. The safety for the firing mechanism includes a block 53 pivotally mounted as at 54 upon the lower tang 15 and as shown in Figure 1, carries a laterally projecting pin 46 to be moved to a 75 position overlying the trigger plate 21 by means

of the leg 55 of a bell crank lever that is pivotally mounted as at 56 upon a bracket 57 rising from the tang 15 with the other leg 58 of the bell crank lever operated by a slide 5 disposed above the upper tang 14 and guided in its movement on the guide members 60 of the gun as illustrated in Figure 1 in its cocked position. With the hammer 25 cocked, the slide plate 40 is moved rearwardly against the tension of the spring 46, the slide plate being guided in its movement through the slots 42 and 42a in the block 18 and tang 15 with the upper rear end 40a of the slide plate 40 positioned rearwardly of the lateral arm 38 carried by the sear 36 of the left hand or second firing mechanism, but 15 when the slide plate 40 is at its limit of rearward movement, the cross pin 31 carried by the trigger plate 21 is still engaged in the slot 47 of the plate 40 so that when the trigger 20 is operated for releasing the right hand or first 20 firing mechanism, the slide plate 40 pivotally moves upon the pivot pin 24 of the trigger that passes through the slide plate slot 43 with the rear end 40a of the slide plate moving upwardly but escaping the lateral arm 38 on the sear 36, 25 this position being illustrated in Figure 2. When the right hand firing mechanism is released as illustrated in Figure 2, the inertia piece 49 swings to the position as illustrated above the block 39 carried by the sear 36 to prevent accidental 30 operation of said sear. When pressure on the trigger is relieved, the spring associated with the sear 28 restores the trigger to the position shown in Figure 3 and at which time the spring 46 moves the slide plate 40 forwardly to position 35 the upper end 40a of the slide plate beneath the cross arm 38 of the sear 36 for the operation of the sear of the left hand or second firing mechanism. As stated, the slide plate is guided in its movement through the slot 42a in the tang 15 and through the slot 42 in the block 18, the forward angle arm extensions 44 and 45 on the slide plate being provided for clearing the bolting mechanism 19 so that the free end of the arm 45 is positioned for engagement with the 40 hammer 25 to be controlled in its operation by 45 said hammer.

While there is herein shown and described the preferred embodiment of the invention, it is nevertheless to be understood that minor 50 changes may be made therein without departing from the spirit and scope of the invention as claimed.

We claim:—

1. In a double barrelled firearm, wherein a 55 separate firing mechanism is provided for each barrel and including a hammer and a sear, wherein in a single trigger is in constant operative relation to one sear and wherein a single slide member is adapted to form connection between the trigger and sear of the other firing mechanism, the gun including a frame carrying upper and lower tangs and the lower tang having a slot 60 therein forming a guide for the slide member, and said slide member having a slot therein receiving the pivot pin of the trigger and constituting position retention means for the slide, and a pin and slot connection between the trigger and slide member whereby the slide member is pivotally movable with the trigger during each operation 65 thereof.

2. In a double barrelled firearm, wherein a 70 separate firing mechanism is provided for each barrel and including a hammer and a sear, wherein in a single trigger is in constant operative rela- 75

- tion to one sear and wherein a slide member is adapted to form connection between the trigger and sear of the other firing mechanism, the gun including a frame carrying upper and lower tangs and the lower tang having a slot therein forming a guide for the slide member, said slide member having a slot therein receiving the pivot pin of the trigger and by which the slide is retained in position, a pin and slot connection between the trigger and slide member whereby the slide member is pivotally movable with the trigger during each operation thereof, a block and post connection between the upper and lower tangs and said block having slots therein aligning with the slots in the lower tang and through which the slide member and trigger move.
3. In a double barrelled firearm, wherein a separate firing mechanism is provided for each barrel and including a hammer and a sear, wherein a single trigger is in constant operative relation to one sear at one side of the frame and wherein a slide member at the other side of the frame is adapted to form connection between the trigger and sear of the other firing mechanism, the gun including a frame carrying upper and lower tangs and the lower tang having a slot therein forming a guide for the slide member, and an angle arm extension on the forward end of the slide member with the terminal end of the extension engaged with the hammer of the first firing mechanism at the other side of the frame permitting forward sliding movement of the slide member into position for operation of the second firing mechanism.
- 35 4. In a double barrelled firearm, wherein a separate firing mechanism is provided for each barrel and including a hammer and a sear, wherein a single trigger is in constant operative relation to one sear and wherein a slide member is adapted to form connection between the trigger and sear of the other firing mechanism, the gun including a frame carrying upper and lower tangs and the lower tang having a slot therein forming a guide for the slide member, said slide member having a slot therein receiving the pivot pin of the trigger, a pin and slot connection between the trigger and slide member whereby the slide member is pivotally movable with the trigger, and an angle arm extension on the forward end of the slide member with the terminal end of the extension engaged with the hammer of the first firing mechanism permitting forward sliding movement of the slide member.
5. In a double barrelled firearm, wherein a separate firing mechanism is provided for each barrel and including a hammer and a sear, wherein a single trigger is in constant operative relation to one sear and wherein a slide member is adapted to form connection between the trigger and sear of the other firing mechanism, the gun including a frame carrying upper and lower tangs and the lower tang having a slot therein forming a guide for the slide member, a block and post connection between the upper and lower tangs and said block having slots therein aligning with the slots in the lower tang and through which the slide member and trigger move, and an angle arm extension on the forward end of the slide member with the terminal end of the extension engaged with the hammer of the first firing mechanism permitting forward sliding movement of the slide member.
6. In a double barrelled firearm, wherein a separate firing mechanism is provided for each barrel and including a hammer and a sear, wherein a single trigger is in constant operative relation to one sear and wherein a slide member is adapted to form connection between the trigger and sear of the other firing mechanism, the gun including a frame carrying upper and lower tangs and the lower tang having a slot therein forming a guide for the slide member, said slide member having a slot therein receiving the pivot pin of the trigger, a pin and slot connection between the trigger and slide member whereby the slide member is pivotally movable with the trigger, a block and post connection between the upper and lower tangs and said block having slots therein aligning with the slots in the lower tang and through which the slide member and trigger move, and angle arm extension on the forward end of the slide member with the terminal end of the extension engaged with the hammer of the first firing mechanism permitting forward sliding movement of the slide member.
7. In a double barrelled firearm, wherein a separate firing mechanism is provided for each barrel and including a hammer and a sear, wherein a single trigger is in constant operative relation to one sear and wherein a slide member is adapted to form communication between the trigger and sear of the other firing mechanism, the firearm including a frame carrying upper and lower tangs, bolting mechanism between the tangs at the forward ends, a base block and bolt connection between the ends of the tangs, the lower tang and block being slotted to accommodate the mounting of the trigger and slide member and an angle arm extension on the forward end of the slide member to clear the bolting mechanisms and engaged with the hammer of the first firing mechanism.
8. In a double barrelled firearm, wherein a separate firing mechanism is provided for each barrel and including a hammer and a sear, wherein a single trigger is in constant operative relation to one sear and wherein a slide member is adapted to form connection between the trigger and sear of the other firing mechanism, the gun including a frame carrying upper and lower tangs and the lower tang having a slot therein forming a guide for the slide member, an abutment block rising from the rear end of the sear of the second firing mechanism and a tensioned inertia piece pivotally suspended above the abutment block to be moved by recoil action into engagement therewith to prevent accidental operation of the second firing mechanism.
